WRINGER

Charles W. Williams, Shaker Heights, Ohio, assignor to Automatic Safety Wringer Company, a partnership composed of Charles B. Williams, Shaker Heights, Horace B. Fay, Willoughby, and Charles W. Williams, Shaker Heights, Ohio

Continuation of application Serial No. 143,522, May 19, 1947. This application November 27, 1942, Serial No. 467,282.

10 Claims. (Cl. 68—253)

This invention relates to a clothes wringer embodying the important characteristics of efficiently removing liquid from the clothes and affording safety to the operator and is a continuation of my application Serial No. 143,522, filed May 19, 1937.

The general object of this invention has been to produce a multiple roll wringer employing preferably three rolls positioned in such manner that one roll is common to the other two and provides two roll bites therewith. Thus clothes are fed to the wringer from side to side passing from one roll bite to the other. This wringer is of distinctive construction in that the common roll is shiftably urged against the other rolls by the pressure spring mechanism. Thus, the roll is not only adapted to be power driven but may shift up and down without breaking the drive connecting it with the power head.

Mechanism is provided and becomes active on a predetermined separation between two of the rolls to stop the operation of the wringer. My wringer thus operates in general in such manner that the initial or intake roll bite employs a comparatively light pressure between the rolls and acts not only to prevent the operator from feeding her hands into the pressure roll bite, but serves to actuate a release which stops the wringer if her hands pass too far into the same.

More specific objects of my invention will become apparent from the following description when construed in the light of the accompanying drawings and the important characteristics are set out in the claims.

In the annexed drawings:

Fig. 1 is a side elevation of my improved clothes wringer;

Fig. 2 is a vertical section through Fig. 1 with parts in section and other parts omitted;

Figs. 3, 4, 5 and 6 are sections through Fig. 2 as indicated by the lines 3—3, 4—4, 5—5 and 6—6, respectively, with certain parts omitted;

Figs. 7 and 8 are similar to Fig. 3 and show the safety mechanism in different operating positions;

Fig. 9 is a detail showing the type of drive gears employed; and

Fig. 10 is a detail showing the cam track employed in connection with the roll reversing mechanism.

Referring now to the drawings, Fig. 1 shows my wringer as employing a substantially conventional head 15 having a power engagement 16 with the wringer post of an ordinary washing machine. The main body 18 of the wringer is secured to the head and carries pivotally mounted thereon a

cover 20 hinged thereto as at 22. Suitable latch mechanism may be employed to retain the cover and the body in closed relation to each other and yet permit their ready separation on opening the wringer.

The drive for the wringer, as above stated, is taken from the wringer post at 16 and transmitted into the head to a bevel gear 25, Fig. 2. This gear in turn meshes with two bevel gears 27 and 28, idly carried on a short shaft 30 extending into the wringer body. Rigidly secured to the shaft 30 between the adjacent bevel gears is a clutch 32. The body end of the shaft 30 has secured to it a clutch pulley member 35 and also a gear 37 so carried that the shaft may slide with respect thereto. It will thus be seen that as the clutch member 35 is moved back and forth in the manner hereinafter to be described, the clutch 32 will engage either the bevel gear 27 or 28 as desired and drive the gear 37, either clockwise or counterclockwise.

Of the three rolls employed in my wringer I prefer to make the top one the power driven roll. To this end the top roll, indicated at 40, is carried in the cover 20 and has secured to its shaft adjacent the head end a gear 42 adapted to mesh with the gear 37. These gears are of the construction shown in Fig. 9. As illustrated in that figure each gear comprises two sets of teeth 31 and 42 spaced side by side and with the teeth of one set positioned circumferentially opposite the open space between the teeth of the other side. This enables the teeth to be circumferentially spaced a considerable distance apart and thus the gears 31 and 42 may separate to a considerable extent and still maintain a drive. The peculiar tooth configuration of Fig. 9 also facilitates this separable drive by affording clearance between the contacting teeth. It will be noted by those skilled in the art that these gears are fairly common in washing machines.

The upper roll 40, as above stated, is the roll shiftably carried against the pressure of the pressure springs and the mounting of this roll is best shown in Figs. 2 and 5. It will there be seen that the top 20 embodies at each end thereof a cross-rib 45 which, at its center, is shaped to form an upwardly opening slideway 47 with vertical guiding ribs 48. The two upper roll journal blocks 50 are carried in the said slideways and guided therein by pins 52 occupying the vertical opening between the ribs 48. Downward movement of the journal blocks is limited by the underlying bottom of the pockets 41.

Wringing pressure is applied against the top

of the said journal blocks 50 by suitable spring pressure mechanism carried in the cover 20. As shown in Fig. 5, this comprises a pair of pressure springs 55 bearing at one end around a boss on the ribs 45, held in place by nuts 58 carrying washers 57 threaded to restrain bolts 60. These bolts slidably pass through the aforementioned bosses in the ribs 45 and terminate at their upper ends in yokes 62. Fulcrum bars 65 are pivotally carried in the yokes and bear at one end against the journal blocks 50 and at the other end against wear plates 67 integral with the ribs 45. Thus the tendency of the springs 55 to expand applies wringing pressure to the journal blocks 50 and through them to the roll 40 carried therein in bushings 69.

The two lower rolls, coacting with the top roll 40, are indicated generally at 70 and 75 and are carried in the body portion 18. Each roll is seated at its ends in heavy bronze bushings 71, which in turn lie in slots of tieplates 80 at each end of the wringer and thus maintain the lower rolls in proper relation to each other. In the center of each tieplate is a slot 82, in which is slidably carried a guide 85, which as shown in Fig. 4 lies between the lower rolls, and which strips clothes therefrom and prevents their passage downwardly between the rolls, thus insuring feeding of the clothes properly through the wringer. The rolls 70 and 75 are normally retained upwardly either against the roll 40 or, if the top is open, against edges 86 of body cross-ribs 88 by four light springs 90 secured at one end to the plates 80 and at the other end to the said ribs 88. The springs are light enough to permit the feeding of an operator's hand between the top roll and one of the lower rolls without harm to the same, although preferably this pressure is sufficient to pinch the fingers enough to cause the operator to instinctively draw her hand out of the roll bite. As indicated above, when the top is closed the rolls 70 and 75 contact the top roll 40 and are positioned slightly below the upper edge 86 and thus the only purpose served by the upper edges 86 is to prevent excessive upward movement of the lower rolls when the top is opened.

Since the lower rolls would normally be free to move downwardly except for the light pressure of the springs 90, there would ordinarily be no wringing pressure set up by the two springs 55 acting against the top roll. My wringer is so constructed that either of the lower rolls desired may be forced upwardly against the roll 40 and retained fixedly in position to establish the requisite wringing pressure between that roll and the top roll. When so held the other lower roll is free to drop downwardly except for the light springs 90. When this condition is created the lower roll, locked in position, coacts with the top roll to establish the necessary wringing pressure through the medium of the springs 55 and the other lower roll coacts with the top roll to provide a light pressure intake bite. It is important that one of the lower rolls is locked against the upper roll it forces the same upwardly enough to push the top roll away from the bottom of the pockets 47 and thus establish wringing pressure between the rolls before clothes are fed to the wringer. As will be hereinafter shown, the operating mechanism for the lower rolls just described may be shifted to enable either lower roll to operate as the auxiliary intake roll or as the second pressure roll.

A pair of cams 95 rotatably carried on a shaft 100 lock either lower roll desired in position as a pressure roll. The periphery of these cams, 75

as shown for instance in Fig. 3, is substantially circular with a segment removed along a chord of the cam outer circle. It will be seen that the cam outer face departs from a true circle and tapers inwardly adjacent the cut-off portion as indicated between the arrows in Fig. 3 and marked "X." The shaft 100 is journaled in members 102 and secured to the bottom of the body 18. At the end opposite the head the shaft 100 protrudes through the body wall and has mounted thereon a handle 105.

Either lower roll desired is forced upwardly against the roll 40 by swinging the handle 105 and with it the two cams 95 either clockwise or counterclockwise, depending upon which lower roll is to be positioned. As shown in Fig. 3, the handle has been shifted clockwise and the left-hand tapered surface X of the cams 95 has forced the bushings 71 of the roll 75 upwardly to establish wringing pressure between that roll and roll 40. It will be apparent from the figure that, due to the cut-out portions of the cams 95, the roll 70 is free to drop downwardly against the action of the springs 90. In similar manner, if the handle 105 were rotated counterclockwise the right-hand tapered surface X of the cam 95, Fig. 3, would underlie the bushings of the roll 70 and that roll would coact with the top roll to provide a pressure bite.

30 Latches are provided to abut the cams 95 in either of their active positions and retain the same locked. These latches are indicated at 110 and carried on lengthwise extending shafts 115 along both sides of the wringer. Each shaft carries two latches, thus providing a pair coacting with each cam 95. The latches are normally urged upwardly in the position shown at the right-hand side of Fig. 3 by light shaft springs bearing at one end against the latch and at the other end against any convenient portion of the body 18. The upward movement of the latches is limited by mating abutments located at 118 in the latch and rigid with the frame 18.

45 Steel pins are embedded in the cams 95 to contact the latches and maintain the cams in predetermined position. These pins are indicated at 120 and are engaged by an inturned flange of the latches 110, as best shown in Fig. 6. As shown in Fig. 3, the right-hand latch is locked behind the right-hand pin 120, maintaining the roll 75 in position to provide a pressure roll bite. At the same time the inturned flange of the left-hand latch 110 lies idly against the edge of the upstanding portion 122 and is inactive.

55 The latches 110 may be manually depressed to permit rocking of the cams 95 to an inactive position, removing the pressure from the pressure rolls. To this end there is secured at the right-hand end of the shaft 100, Fig. 2, an upstanding arm 130, to which is attached a tension spring 135 carried at its other end in a pin 137 of the body 18. As shown in Fig. 6, when the cams 95 are in either active position the arm 130 is so positioned that the spring 135 is under tension. Thus, when the latches 110 are rocked out of engagement with the coacting pins 120 the tendency of the spring to contract pulls the arm 130 upwardly and rocks the cams 95 to a neutral position, releasing the pressure from either lower roll.

60 The latches 110 may be manually depressed by the knobs 140 carried in the top 20. A stamping 145 connects each knob with each underlying pair of latches. This stamping, as shown in Fig. 3, is yoked at the top and bottom to pass beyond

the shaft of the roll 40 and the shaft 100 respectively. The shaft 100 is annularly recessed as shown in that figure to prevent the lower end of the stamping 145 from slipping sidewise. This construction is also shown in Fig. 2. The upper end of the stamping 145 is retained from sidewise motion by the slot and pin construction 147, in which the pins are carried in the cross-ribs 88. The knobs 140 are retained lightly against one arm of the upper yoke of the stamping 145 by light springs 150 sufficient to prevent rattling of the parts and yet not sufficient to depress the latches 110, against which the lower arms of the stamping 145 bear. It will thus be seen that as either knob 140 is depressed it acts through its coacting stamping 145 to depress one of the active latches holding the cams 95 in position. Since the active latches are connected on the rock shaft 115, both will rock simultaneously. Thus each latch drops out of position behind the pins 120 and under the action of the spring 135 the cams are returned to a neutral position, relieving all wringing pressure from the rolls.

Rocking of the cams 95 also effects the drive to the head of the roll 40. The cam adjacent the head end of the wringer is provided on its under and outer periphery with a cam slot 160, and best shown in Fig. 10 is development. A rock arm 165, Figs. 5, 7 and 8, is pivoted to the body 18 at 167 and terminates at its outer edge in a pin 170 lying in cam slot 160 of the cam 95 adjacent the drive end of the wringer, i. e. the left-hand side of Fig. 2. A second rock arm 175, Fig. 2, also pivoted to the frame 18 to rock about a vertical axis has a pin in one arm lying in the annular recess of the clutch 35. This arm is connected by a link 177 with the pin 178 of the arm 165. It thus follows that as the cam 95 is rocked sufficiently to cause the pin 170 to traverse either portion marked "A" of the slot 160, the clutch 35, through the medium of the arm 175 and the link 177, will be rocked from engagement to inactive position and disconnect the clutch 32 from either bevel gear 27 or 28. During travel of the pin 170 through the portion B of the cam slot there is no shifting of the clutch.

The mechanism just described is utilized to provide an automatic stop for the wringer when the lower roll, acting as an intake roll, drops a predetermined amount. When this takes place an edge of the plates 80 contacts an inturned flanged top of adjacent latches 110 and forces the same downwardly, dropping them from behind the pins 120 and enabling the cams 95 to be rotated by the spring 135. This rotation is stopped because the pin engaging portion of the latches will abut a second set of pins 180 carried in the cams 95, Fig. 7. The distance of travel permitted between the two sets of pins is sufficient to enable the pin 170 to travel the length of either cam groove portion A and thus, as before described, stop the rotation of the wringer.

This is accomplished without relieving the pressure between the pressure rolls because the cams do not rock far enough to cease contact between the tapered surfaces X thereof and the bushings 77, with which they are in engagement. The pressure is released by depressing the knob 140 and rocking the latches 110 out of engagement with the second set of pins 180, whereupon the spring 135 is free to draw the cams 95 to a completely neutral position.

It has been found desirable to require two motions in the operation of my wringer, one, which

may be either manual or automatic, acting to stop the roll rotation, and the second, which must be manual, to release the wringing pressure. It will be apparent that the construction shown may be adapted to permit an automatic and simultaneous stopping of the wringer with release of pressure.

I have shown several minor features of my invention which improve the operation thereof. For instance, as shown in Figs. 2 and 6, I have placed a pulley 200 on each of the lower roll shafts and connected the same by a resilient rubber belt. The purpose of this is to insure rotation of the auxiliary roll through the more or less positively driven pressure roll if there is any tendency of the clothes to cause the aforesaid auxiliary roll to slip when they are fed thereto due to the light pressure normally maintained at the auxiliary roll bite.

Stripping boards 210, as shown in Fig. 4, are carried on the latch shafts 115 and maintained by light springs, not shown, against the lower rolls 70 and 75 to strip clothes therefrom as they leave the wringer and prevent any tendency of the same to wrap around the rolls. These boards are so shaped that they remain active as either roll drops under the impulse of clothes fed thereto. Strippers 215 are provided, secured to the central top rib and functioning in like manner in conjunction with the upper roll 40. A drain board or guide 100 is mounted on the shaft 100.

It will be seen from the foregoing description that I have invented a novel, efficient and safe clothes wringer such as described and now summarized in the claims.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A wringer comprising a main frame and a movable top frame, a roll carried by the top frame, two rolls carried by the bottom frame in position to establish a pair of roll bites, pressure mechanism carried by and movable with said top frame to coact directly with the top roll and shiftable means to establish wringing pressure between the top roll and either of the lower rolls as desired.

2. In a wringer, a main frame, a top frame carried thereby, a pair of rolls movably carried

55 by the main frame, a roll carried by the top frame and coacting with the other two rolls to

provide a pair of roll bites, pressure mechanism

partially carried by the top frame, cams rotatably carried by the main frame and rotatable to

60 underlie either lower roll desired to establish

wringing pressure between the top roll and either

lower roll, and means for automatically releasing

the cams from said underlying position when

a predetermined thickness of material is fed to

the wringer to stop rotation of the wringer.

3. In a wringer, a frame, three rolls carried in

said frame in position to establish a pair of roll

bites, pressure mechanism to establish wringing

pressure at either roll bite desired, power means

70 to drive said wringer, reversible means to reverse

the direction of said rolls and said pressure mech-

anism including cams shiftable to establish said

wringing pressure at either bite desired and con-

trol the direction of rotation of said rolls, and

75 means to maintain the cams in any one of five

positions, two positions maintaining wringing pressure at respective roll bites and connecting the rolls to the drive means to rotate the same in the desired direction, two positions stopping the roll rotation without releasing the wringing pressure and the fifth position releasing the wringing pressure from both roll bites and stopping the roll rotation.

4. In a wringer, a frame, three rolls carried in said frame with one roll common to the other two to establish a pair of clothes gripping bites, mechanism to urge said one roll and either of said pair of rolls together to establish a clothes wringing bite, comprising a shiftable element adapted to urge one of the rolls forming said wringing bite against the other roll, means normally active to shift said element out of coacting position with said roll and a latch to retain said element in coacting position as aforesaid.

5. In a wringer, a frame, three rolls carried thereby and spaced with one roll common to and its surface coacting with each of the other two roll surfaces to provide a pair of roll bites, a shiftable support for said common roll to permit movement of said roll away from said other rolls, resilient pressure mechanism to urge said common roll toward said other two rolls and establish wringing pressure between said common roll and either one of the other rolls as desired, power means to drive said rolls including reverse means and mechanism shiftable to alternately establish wringing pressure between said common roll and either of said other rolls to feed clothes to the wringer from opposite directions as desired, said reversing means being automatically operable upon shifting said shifting member.

6. In a wringer, a frame, three rolls carried by the frame with one roll surface coacting with the roll surface of each of the other two rolls to provide a pair of roll bites, shiftable supports for each roll in said wringer to permit separation of the roll bites, power means to drive said rolls, separable connection means to reverse the direction of rotation of said rolls, common resilient pressure mechanism operable to be effective at one bite or the other to establish wringing pressure at either of said roll bites to feed clothes through said wringer from either of said directions, and linkage mechanism interconnecting said pressure mechanism and said separable reversing means to simultaneously actuate said means to control the operation of said wringer.

7. A wringer comprising a frame, a plurality of rolls in said frame coacting to provide a pair of roll bites, mechanism to establish wringing pressure at either roll bite desired, power means to rotate the rolls and means connected for simultaneous operation and operable to both reverse the direction of rotation of said rolls and release the wringing pressure at the one roll bite and establish wringing pressure at the other roll bite.

8. A wringer comprising a main frame, a top frame, a roll carried in said top frame, a pair of rolls in said main frame and positioned to each coact with the top frame roll to provide a pair of roll bites, mechanism in the main frame and shiftable to coact with either lower roll desired to establish wringing pressure between that roll and the top roll, power means to drive said rolls, reversing means to reverse the direction of rotation of said rolls, and said mechanism being operatively connected to and actuated with the roll reversing means to also shift said pressure bite from one roll bite to the other.

9. In a wringer, a frame, an upper roll and a pair of lower rolls carried therein, each coacting with said upper roll, a shiftable support for said lower rolls alternately to permit one of said rolls to move away from said upper roll as desired and means to engage the other of said lower rolls and prevent movement away from said top roll and spring means bearing on said top roll to urge the same downwardly against said other roll to provide a pressure bite.

10. A wringer comprising a frame, three rolls in said frame with one roll above being resiliently urged toward and coacting with the other two to provide a pair of roll bites, each of said bites opening upwardly, a shiftable support for said lower rolls to permit said rolls to move away from said upper roll, a member shiftable to engage either of said lower rolls as desired and prevent movement of said engaged roll away from said top roll, reversible power means to drive said rolls, a control member and mechanism actuated by shifting said control member to thereby both drivingly connect said rolls for rotation by said power means and also shift said shiftable member to engage one of said lower rolls to place the same in wringing relation with said one roll.

CHARLES W. WILLIAMS.
